UNITED STATES PATENT OFFICE.

HORATIO G. GILLMOR, OF WASHINGTON, DISTRICT OF COLUMBIA.

ANTICREEPER.

Application filed August 28, 1925. Serial No. 53,062.

My invention relates to devices for preventing the longitudinal creeping movement of railroad rails. Such devices are commonly known as anticreepers, rail anchors, rail stays or creepchecks.

It has for its principal object the provision of an anticreeper comprising a body portion and two arms so arranged at the opposite ends thereof that when the device is applied with the arms in operative engagement with the opposite sides of the rail with the body below and out of contact with the bottom of the rail base and the device substantially perpendicular to the longitudinal axis of the rail, the device will be tightened on the rail when the anticreeper is tilted or inclined from the perpendicular.

By my construction I am enabled to provide an anticreeper comprising nothing beyond a bar, provided with a single arm at each end, which arms may be applied in gripping position on the rail, with one end of the bar, in the operative position of the device, engaging the under side of the rail head and the other end of the bar engaging the edge of the rail base. Preferably the device is applied with the body in contact with the tie or other fixed abutment. Following this initial application of the anticreeper, pressure exerted upon the body tending to tilt or incline it from the perpendicular automatically tightens the anticreeper and increases its grip upon the rail.

Preferably also this device is so constructed that when once applied to the rail it can never under service conditions become so loosened as to drop from the rail and if properly proportioned for the particular rail to which it is applied, will at all times have a resilient grip on the rail, which resilient grip is progressively tightened by the forces which tend to cause creeping of the rail.

A further object of my invention is to provide an anticreeper of the bar type, which is fashioned out of a rolled bar and so constructed that the body of the anticreeper may be given any desirable section as width and thickness to successfully resist forces tending to cause breakage and one of the arms may be given such dimensions as to width and thickness as will both successfully resist forces tending to cause breakage and provide maximum resistance to creepage of the rail with minimum weight of the anticreeper.

It is thus the general purpose of my in-

vention to provide a device characterized by simplicity of structure, readiness of application, strength, efficiency, economy of manufacture, durability, and economy of material and having various other advantages as are hereinafter pointed out.

In the more specific embodiment of my invention it is one of my objects to provide an anticreeper comprising an arm at each end so arranged with reference to each other and to the body of the anticreeper that as the anticreeper after application is tilted or inclined from the perpendicular position of the rail, one arm will be operatively tightened on the under side of the head and the upper side of the base of the rail.

It is another object of my invention to provide a construction provided with an arm which may be wedged in between the under surface of the head and the inclined upper surface of the base of the rail at one side of the rail.

Another object of my invention is to provide an anticreeper which may be applied to the rail without the use of special tools or implements other than those usually employed by track hands.

It is also among the objects of my invention to improve devices of this character in sundry details hereinafter pointed out.

The preferred means by which I accomplish my several objects are illustrated in the accompanying drawings, in which:

Figure 1 is an elevation with the rail in section.

Figure 2 is a side elevation with the cross tie in section.

Figure 3 is an elevation with the rail in section illustrating the preliminary positioning of the device on the rail.

Figure 4 is an elevation with the rail in section showing the anticreeper in preliminary position on the rail.

In this embodiment of my invention the device is formed in one piece from a rolled bar of such dimensions as to provide sufficient strength to withstand the stresses to which the body A will be subjected. The body A is provided at one end with an inwardly and upwardly projecting arm B and at the other end with a shorter upwardly and inwardly projecting arm C both formed integrally with the body A. The rail D is of the usual construction and has a head F and base E.

The arm B is arranged to be wedged in

- between the head F and base E of the rail D at one side with the end surface G of the arm B pressed against and gripping the under inclined face of the rail head F and 5 the surface H pressed against and gripping the upper inclined surface of the base E. The arm C is constructed to engage and grip the edge of the base E, put the body A of the anticreeper under tension and 10 retain the longer arm B in position wedged in between the head F and base E at the side of the rail D opposite to that engaged by the arm C.

The arms B and C are so dimensioned and 15 positioned in relation to the body A and to each other that when the anticreeper is in position on the rail the arms B and C are farther apart than they are before application of the device to the rail.

- 20 The arms B and C are formed by bending the bar from which the device is fashioned, and in bending the bar to form the arm B a loop I is formed of such dimension as to provide sufficient internal clearance to permit the device to be preliminarily positioned upon the rail with the body A below the base E and the arms B and C extending above the base E at opposite sides of the rail D as shown in Figure 4.

- 30 It will be noted that in forming the loop I and the arm B the bar is so bent as to provide the surface H, which in the operative position of the device on the rail engages the upper inclined face of the base E some 35 distance in from its edge and as nearly as may conveniently be directly below the engagement of the surface G of the arm B with the under inclined face of the head F.

Before bending the bar to shape it may 40 be flattened at K and the width of that portion of the bar increased with corresponding reduction in the thickness, so that after bending to form and positioning the device on the rail the length of the bearing of the 45 surface H with the upper surface of the base E, longitudinally of the rail will be greater than it would be if the bar were bent to shape without flattening. The bar may also be flattened at L and the width of this 50 portion increased with corresponding increase in the length of the bearing of the surface G on the under inclined face of the head F longitudinally of the rail.

The anticreeper is applied to the rail by 55 inclining it and with the longer arm B in inclined position in the space between the head F and base E of the rail passing the body underneath the rail until the end of the short arm C will clear the edge of the base 60 E at the side of the rail D opposite to the arm B. The position of the anticreeper when the end of the short arm is about to clear the edge of the rail base is illustrated in Figure 3. It will sometimes be necessary 65 to apply force to bring the anticreeper to

the position which will permit the short arm C to clear the edge of the rail base, and when this is necessary one or more blows of a hammer or other suitable implement will suffice. If the device is so proportioned as 70 to provide suitable and sufficient internal clearance in the loop I the anticreeper may be passed to the position illustrated in Figure 4, with the arm C projecting above the base E at one side of the rail D and the end 75 surface of the long arm B just beginning to engage the inclined under surface of the head F at the other side without the use of force. The anticreeper may then be moved longitudinally of the rail until the body A 80 has one face in contact with the tie O. When in the position illustrated in Figure 4 with the long arm end surface G beginning to engage the inclined lower surface of the rail head F and the arm G engaging the upper corner of the base E and one face of the body A in contact with the tie O the device is in preliminary position. Force is required to effect the final positioning of the 85 anticreeper on the rail. This may best be 90 effected by driving the upper end of the long arm B toward the rail by blows of a hammer directed as indicated by the arrow P and by driving the short arm down by 95 blows directed as indicated by the arrow M in Figure 4. When the inner corner of the arm C has thus been forced down by the upper corner of the base E and into contact with the vertical edge of the base E the arm 100 B will be tightly wedged in between the head F and base E. The head F will then be pressed upon and gripped by the surface G and the base E pressed upon and gripped by the surface H of the arm B and the device locked in position by the engagement of the arm C with the base E at the 105 other side of the rail D. Forcing the anticreeper to position in the manner described spreads the arms C and B apart and the resiliency of the anticreeper causes it to exert 110 continuous pressure upon the rail.

The direction in which the rail tends to 115 creep is indicated by the arrow in Figure 2. It will readily be understood that with the device in the final operative position shown in Figures 1 and 2 the grip upon the head and upper surface of the base of the rail at one side and upon the edge of the base at the other side of the rail and the contact of the body A with the tie O will prevent movement of the rail forward, that is in the direction of the arrow in Figure 2. If, however, the initial grip of the device on the rail be not sufficient to effectually resist the forces exerted by the tendency of the rail 125 to creep slight movements of the rail forward will cause the arm B to assume a tilted or inclined position from the perpendicular as indicated by the dotted lines in Figure 2, because the body A will be held by its con- 130

tact with the tie O and the grip of the surface G of the arm B will cause it to be carried forward with the rail. This tilting of the arm B will automatically increase the grip of the arm B on the head and base of the rail and thus automatically increase the resistance to further forward movement of the rail.

It will readily be seen the increasing the 10 length of the surface G in contact with the head F or increasing the length of the surface H in contact with the base E increases the increment in gripping force set up on slight forward or creeping movement of the 15 rail and that therefore it is possible by my construction to make the body of the anti-creep of the minimum dimensions necessary for the needed strength and secure the desired grip needed to hold the rail against 20 creeping by so relating the width and thickness of the portions K and L of the arm B as to secure the gripping action desired with slight forward movement of the rail.

The engagement of the surface of the 25 arm B with the upper inclined face of the base E of the rail at some distance in from the edge of the base and as near as possible below the engagement of the surface G with the under surface of the head F causes the 30 portion of the arm B which is wedged in between the head and base to be almost entirely under compression stress and makes the gripping action more effective.

To remove the device from the rail the 35 arm C may be driven down by blows directed as indicated by the arrow N in Figure 1. The friction of the contact of the short arm C with the edge of the rail base E is sufficient to permit this to be done progressively and the resiliency of the body A will permit it to be deflected and assume in 40 succession positions, one of which is shown by the dotted lines in Figure 1, until the lower corner of the base E is passed by the 45 end of the arm C. The anticreeper will then spring off the rail and resume the form which it had when in its original unstressed condition.

By my invention, I provide a very simple 50 and strong device which may be formed from a rolled bar with a minimum of operations requiring a minimum of material and labor in manufacture, capable of being easily and quickly applied to the rail and 55 affording a maximum of efficiency.

Having described my invention, what I claim is:

1. A one piece anticreeper consisting of 60 a bar having a body portion adapted to engage a tie but not the rail bottom and rail gripping arms formed on the ends of said bar, one of said arms being so formed as to provide a rail head gripping surface extending forward of the forward face and back of 65 the rear face of said body portion.

2. A rail anchor comprising a bar adapted to be applied to a rail transversely thereof and provided with a relatively short arm adapted to engage the rail base at one side of the rail and a relatively long arm having 70 its extremity reduced in thickness and increased in width adapted to be forced in between the head and base of the rail at the other side of the rail.

3. A device for preventing the creeping 75 of rails comprising a bar bent to form a body portion adapted to engage a tie but not the bottom of the rail base and end arms of unequal length the longer adapted to engage and grip both the head and base of the 80 rail at one side with surfaces extending forward of the forward side and back of the rear side of said body portion and the shorter adapted to engage and grip the rail base at the other side of the rail. 85

4. A one piece anticreeper comprising a bar fashioned to provide a body adapted to be held out of contact with the bottom of the rail base and to engage a tie in opposition to the tendency of the rail to creep and 90 terminal arms one of which has portions reduced in thickness and increased in width engaging and gripping the head and base of the rail at one side and the other of which engages and grips the rail base at the other 95 side of the rail.

5. An anticreeper formed of a single bar of metal bent to form a body portion adapted to engage a crosstie but not the rail base, 100 an arm at one end adapted to grip the edge of the rail base at one side of the rail and an arm at the other end thereof adapted to engage the upper surface of the rail base in spaced relation to the edge thereof and to engage and grip the under side of the rail 105 head at the other side of the rail.

6. An anticreeper comprising a bar having a body portion adapted to engage a tie but not the bottom of the rail base and rail gripping arms formed on the ends of said 110 bar, one of said arms being formed to engage and grip the upper surface of the rail base in spaced relation to the edge thereof and to engage and grip the under surface of the rail head forwardly and rearwardly 115 of the planes of the front and rear edges of said body portion.

7. A rail anchor comprising a bar fashioned with a body portion adapted to be held in spaced relation to the rail base 120 and to engage a tie in opposition to the tendency of the rail to creep and end arms adapted to engage the rail base at one side and the rail head and base in spaced relation to the base edge at the other side of 125 the rail one of said arms having portions reduced in thickness and increased in width adjacent the rail base and the rail head.

8. A one piece anticreeper comprising a bar bent to provide a body portion adapted 130

4
to engage a tie but not the rail base and arms extending upwardly and inwardly from said body and adapted to engage and grip the rail base at both sides and the rail head at one side of the rail and having the rail heads engaging portion of said bar elongated.

9. An anticreeper for rails comprising a single bar of metal fashioned to provide a body portion adapted to engage a cross tie in opposition to the tendency of the rail to creep and to be held out of contact with the rail base an arm adapted to grip the edge of the rail base at one side and an arm having a portion reduced in thickness and increased in width adapted to engage the upper surface of the rail base in spaced relation to the edge thereof and to engage and grip the under side of the rail head at the other side of the rail.

10. A rail anchor formed from a single

bar of metal bent to form a body portion adapted to engage a cross tie but not the rail base and end arms of unequal length adapted to engage the rail head and base at one side and the rail base at the other side of the rail, said bar being flattened and widened locally to extend the engagement of the longer arm with the head and base of the rail.

11. A device for preventing the creeping of rails comprising means extending transversely under but out of contact with the rail base a short arm connected with one end of said means bearing upon the edge of the rail base and a long arm connected with the other end of said means bearing against the upper surface of the rail base inwardly from and not at the edge thereof and bearing upon the under surface of the rail head.

H. G. GILLMOR.
